SAFETY BELT BUCKLE

Frederick C. Paller, Jr., Northridge, Calif., assignor to Superior Industries, Inc., Van Nuys, Calif., a corporation of California

Filed Apr. 6, 1962, Ser. No. 185,647

1 Claim. (Cl. 24—77)

The present invention relates generally to belt buckles and more particularly to buckles used to releasably secure the ends of safety belts of the type commonly used in airplanes and automobiles to restrain the occupants in the event of a crash or accident.

It is a major object of the present invention to provide a safety belt buckle which is light in weight, compact in size and yet sufficiently rugged to withstand any load which may be applied to it.

Another object of the present invention is to provide a safety belt buckle which may be readily coupled and uncoupled with a minimum of skill or attention on the part of the user. The belt of the present invention will remain coupled even under extremely adverse conditions, yet may be quickly uncoupled when necessary to permit the extraction of an injured or dazed passenger from a crashed vehicle. This is an extremely important feature since the possibility of a fire occurring after a crash makes it important that immobilized passengers be quickly removed after a crash.

A further object of the present invention is to provide a safety belt buckle which lends itself to low manufacturing cost whereby it will appeal to a wide market.

An additional object of the present invention is to provide a safety belt buckle of the aforescribed nature which permits the length of the safety belt to be easily and rapidly adjusted.

These and other objects and advantages of the present invention will become apparent from the following detailed description, when taken in conjunction with the appended drawings wherein:

FIGURE 1 is a perspective view showing a safety belt buckle embodying the present invention;

FIGURE 2 is a central vertical sectional view taken on line 2—2 of FIGURE 1;

FIGURE 3 is a view similar to FIGURE 2, but showing the parts of said buckle in position to be uncoupled;

FIGURE 4 is a vertical sectional view taken on line 4—4 of FIGURE 2; and

FIGURE 5 is a fragmentary sectional view taken in enlarged scale along the line 5—5 of FIGURE 4.

Referring to the drawings, a preferred form of safety belt buckle embodying the present invention is shown in conjunction with two strap or belt sections designated B and B'. The buckle includes a locking member L and a tongue member T. It should be understood that the tongue member T is releasably coupled with the locking member L to secure the free ends of the belt sections B and B' together.

The locking member L includes a body, generally designated 24, having a flat plate 30 providing a guiding tongue at its front portion and a horizontal generally L-shaped cross-arm 32 at the rear portion of said body. A pair of integral upstanding side walls 34 and 36 extend from the sides of the plate 30 rearwardly of the guiding tongue and from the sides of the cross-arm 32. The plate 30 is formed with a plurality, such as three, upwardly and rearwardly inclined projections 40, 42 and 44. The middle projection 42 is formed on the longitudinal center-line of the body 24, while the projections 40 and 44 are preferably spaced transversely from the center-line an equal distance. The cross-arm 32 is integrally formed at its front end with an upstanding lip 48. The side walls

2

34 and 36 are provided with horizontally aligned, rearwardly and downwardly extending slots 46.

A pivot pin 50 extends transversely between the upper front portions of the side walls 34 and 36 and is rigid relative to these walls. The pivot pin 50 supports a latch, generally designated 60, for pivotal movement relative to the body 24, as indicated in FIGURES 2 and 3. The latch 60 includes a generally rectangular lever 62 having depending side flanges 63 and 64. A torsion spring 65 normally holds the lever 62 flush relative to the upper edges of the body side walls 34 and 36, with the flanges 63 and 64 in snug engagement with the interior surfaces of these side walls and the underside of lever 62 abutting the upper end of cross-arm 32. The front end of the latch 60 is formed with a downwardly and rearwardly extending front wall 66, with the lower edge of the front wall 66 being formed with a rearwardly and upwardly extending cam shoulder 67. The torsion spring 65 has its major portion wrapped about the pivot pin 50, with one end 68 of the spring being inserted within a bore 69 formed in this pin. The opposite end 70 of the spring 65 is wedged into the interior intersecting surfaces of the front wall 66 and the cam element 67.

The tongue member T includes a horizontal plate 71 having a flat tongue 72 formed at its front portion. The intermediate portion of the plate 71 is formed with a transversely extending elongated slot 73 for receiving a looped end 74 of the belt portion B'. As indicated clearly in FIGURE 1, the looped end 74 overlaps and the overlapped belt ends are permanently stitched together as indicated at 75. The front portion of the tongue 72 is formed with a plurality of apertures 76, 77 and 78 corresponding in number and spacing to the number and spacing of the projections 40, 42 and 44 of locking member L. The length and width of the apertures 76, 77 and 78 are just slightly larger in dimension than the length and width of the projections 40, 42 and 44. The sides of the plate 71 rearwardly of the tongue 72 are formed with integral upstanding walls 79 and 80 that extend slightly transversely outwardly relative to the width of tongue 72.

The aforementioned slots 46 formed in the side walls 34 and 36 of the body 24 slidably receive the opposite ends of a transverse strap bar 82 which preferably has a knurled or roughened exterior surface. For this purpose, the strap bar 82 has reduced and flattened end portions 83. This construction permits limited movement of the strap bar 82 in a direction longitudinally of the slots 46. The end of the belt portion B' adjacent the locking member L is threaded upwardly from the underside of body 24 around the strap bar 82 and then downwardly and rearwardly along the front and lower surfaces of the cross-arm 32. With this construction, the length of seat belt portion B may be readily adjusted in the buckle while at the same time whenever any tension is placed upon the seat belt the strap bar 82 is pulled towards the rearward end of the slots 46 wedging and clamping the overlapped end 84 of the seat belt portion B against the cross-arm 32.

In the use of the aforescribed buckle, the effective length of the belt section B may first be adjusted utilizing the strap bar 82. In this regard, the strap bar 82 will be urged forwardly in the slots 46 whenever it is desired to tighten or slacken the overlapped end 84 of the belt portion B. In order to couple the locking member L to the tongue member T the tongue 72 is inserted into the front end of the body 24. Upon entering the front end of the body 24 the forward end of the tongue 72 will deflect the latch L counter-clockwise relative to its normal position. Thereafter, the latch 60 will snap clockwise to its normal position under the influence of the spring 69.

The parts of the buckle will then appear as shown in FIGURES 1 and 2.

Referring particularly to FIGURE 2, it will be noted that the cam element 67 of the latch 60 positively locks the tongue 72 against upward movement relative to the front plate 30. The abutment of the front end of the projections 40, 42 and 44 with the front end of the apertures 76, 77 and 78 will prevent any longitudinal separation of the locking member L and the tongue member T. It should be particularly noted that any longitudinal forces tending to separate the locking member L and the tongue member T will pass directly from the tongue 72 to the front plate 30 of the base 24. Thus, these loads need not be transferred through any intermediate parts as is the case with conventional safety belt buckles. The engagement of the walls 79 and 80 of the tongue member T with the front edges of the side walls 34 and 36 restrains relative longitudinal movement of these parts towards one another.

It should be noted also that inasmuch as the latch lever 20 60 is held flush with and overlies the upper edges of the body side walls 34 and 36, the danger that the latch 60 might become caught on a user's clothing and become inadvertently opened is eliminated. Further, the provision of three transversely spaced sets of locking projections 40, 42 and 44 and apertures 76, 77 and 78 insures even load distribution across the width of the locking member L and the tongue member T.

In order to uncouple the latch member L and the tongue member T the user merely raises the rear end of 30 the latch member L in a counter-clockwise direction, as indicated in FIGURE 3. The tongue 72 may then readily be withdrawn from its engagement with the front plate 30 of body 24. It will be apparent that this uncoupling may take place regardless of the amount of tension being 35 applied between the locked member L and the tongue member T. This is of great importance should it become necessary to remove an occupant of a crashed automobile or aircraft and the weight of the occupant is applying tension between the lock member L and the tongue member T.

Another advantage of the aforescribed buckle is that because of the uniform spacing of the projections 40, 42 and 44 and apertures 76, 77 and 78 the tongue member T may be coupled to the locking member L even though 45 the belt portions B, B' may be twisted. Hence, a user may couple the belt portions very rapidly if he has not previously done so and an emergency presents itself.

Various modifications and changes may be made with 50 respect to the foregoing detailed description without departing from the spirit of the invention or the scope of the following claim.

I claim:

A buckle for use with first and second safety belt portions, comprising:

a locking member body that includes a transverse horizontal plate providing a guiding tongue at its front portion and a transverse cross-bar at the rear portion of said body, with a pair of vertical side walls connecting said plate and said cross-bar and a plurality of transversely spaced, upwardly and rearwardly inclined projections being formed on said

5

4
plate, said guiding tongue projecting beyond said side walls, said cross-bar extending between said side walls and substantially closing the space therebetween;

a transverse pivot pin extending between and secured to said side walls;

a single piece stamped metal latch carried by said pivot pin, said latch integrally including a lever that normally covers the space between the upper ends of said side walls, said lever having depending vertically relatively short side flanges, said latch also having an integral downwardly extending solid front wall extending between said side walls and formed at its lower portion with a cam wall normally horizontally overlying the rear portion of said projections;

a torsion spring wrapped about said pivot pin with one end anchored to said pin and the other end engaging said front wall of said latch to bias said latch toward its normal position;

means on said locking member body that cooperate with said cross-bar to adjustably receive one end of said first belt portion;

and a tongue member secured to said second belt portion, said tongue member having a flat tongue formed with a plurality of apertures complementary to said projections, said tongue member being releasably coupled to said locking member body by inserting said flat tongue between said side walls above and along said guiding tongue of said plate until said apertures register with said projections, said latch being manually pivoted out of its normal position to permit said insertion of said flat tongue, with said spring thereafter automatically snapping said latch back into its normal position wherein the side flanges of said latch lever are in snug engagement with the side walls of said locking member body and the underside of said flanges abut the upper end of said cross-bar, and the front wall of said latch covers the space between the front portion of said side walls above said flat tongue, with the cam wall of said latch locking said flat tongue against upward movement away from the plate of said locking member body, and the projections of said plate and the apertures of said tongue having uniform spacing relative to the longitudinal centerline of said plate whereby said tongue member may be coupled with said locking member body without requiring either member to be inverted.
